UNITED STATES PATENT OFFICE.

ROBERT J. BRENK, OF MILWAUKEE, WISCONSIN.

VEST.

1,322,527.

Specification of Letters Patent. Patented Nov. 25, 1919.

Application filed June 28, 1919. Serial No. 307,320.

To all whom it may concern:

Be it known that I, ROBERT J. BRENK, a citizen of the United States, and resident of Milwaukee, in the county of Milwaukee, 5 and State of Wisconsin, have invented new and useful Improvements in Vests, of which the following is a description, reference being had to the accompanying drawings, which are a part of this specification.

10 The present invention relates to certain new and useful improvements in vests, and has for its primary object to provide means carried by the vest and engaging the trousers near their top for supporting the same 15 at the front where they are most apt to sag, and to retain the shirt from riding over the trouser top.

Another object of this invention is to provide means carried by the vest and having 20 a detachable connection with the trousers whereby the vest will be maintained in its proper position and at all times present a smooth front.

A further object of this invention is to 25 provide a vest having a tab secured to the inner side thereof adjacent one corner of the lower pocket so that the corner stitches of the pocket will provide an additional securing means for the tab where the strain 30 thereon is greatest, and to also provide a button connection between the tab and a lower garment.

With the above and other objects in view which will appear as the description proceeds, my invention resides in the novel construction, combination and arrangement of parts substantially as hereinafter described and more particularly defined by the appended claims, it being understood that such 40 changes in the precise embodiment of the hereindisclosed invention may be made as come within the scope of the claims.

In the accompanying drawing, I have illustrated one complete example of the 45 physical embodiment of my invention constructed according to the best mode I have so far devised for the practical application of the principles thereof, and in which:

Figure 1 is a view of my invention in use 50 with one side of the vest turned back and the tab disconnected for the purpose of illustration.

Fig. 2 is a front plan view of the lower half of one side of a vest embodying my invention, and

Fig. 3 is a view similar to Fig. 2 of the

inner side of the vest illustrating the manner of securing the tab to the vest.

Referring now more particularly to the accompanying drawing, 5 designates a vest of the usual construction having therein lower pockets 6; 7 designates a pair of trousers; and 8 a tab carried by the vest and having a detachable connection with the trouser top as will be later described. 65

The tab 8 is secured to the inner side of the vest preferably adjacent the inner corner of each pocket 6 by means of stitching 9 near the top thereof. The stitching 9, as best shown in Fig. 2, is invisible from the outside of the vest, and as best shown in Fig. 3, the tab 8 is further secured to the vest by means of the stitching 10 located at the inner corner of the pocket and which extends through the vest and the tab 75 8. The stitching 10 engages the tab 8 on a line with a button hole 11 located near its lower end and adapted to engage the button 12 carried by the trousers, and thus reinforces the same where the strain is 80 greatest.

As is readily apparent, the addition of the tab 8 does not detract from the appearance of the vest as it is completely concealed on the inside of the vest as is also the stitching 9. It will be obvious that the tab 8 is capable of ready securement to, or detachment from the trouser top and that it will prevent the trousers from sagging, will retain the shirt 13 from riding over the trouser top, and will also maintain the front 90 of the vest in a smooth, unrumpled condition.

What I claim as my invention is:

1. In a garment support of the class described, the combination with an upper garment having a pair of lower pockets provided with stitches near each corner and a lower garment, of a tab secured to the inner side of the upper garment centrally of 100 the stitching of one corner of each pocket, said stitching passing through the tab to reinforce the same, and a detachable button connection between said tab and the lower garment. 105

2. As an article of manufacture, a vest, having a lower pocket provided near each corner with reinforcing stitching arranged substantially vertical, a tab secured to the inner side of the vest by substantially horizontally extending stitches, said tab being disposed adjacent one corner of the pocket 110

so that the reinforcing stitches of the pocket corner pass through the tab at its point where the strain is greatest, and means at the lower end of the tab for making a detachable connection with a lower garment.

3. A garment support of the class described comprising a tab secured to an upper garment adjacent the upper inner corner of a pocket therein, T-shaped stitching securing the tab to said garment, the top hori-

zontal portion of the T being adjacent the top of the tab and the vertical leg portion of the T being centrally of said tab and providing corner stitching for adjacent corner of the pocket, and means for securing the lower end of the tab to a lower garment. 15

In testimony whereof I affix my signature.

ROBERT J. BRENK.
